UNITED STATES PATENT OFFICE

101,118

DESIGN FOR A BRIDGE FOR AN OPHTHALMIC MOUNTING

Henry W. Grom, Rochester, N. Y.

Application March 5, 1936, Serial No. 61,496

Term of patent 14 years

To whom it may concern:

Be it known that I, Henry W. Grom, a citizen of the United States of America, residing in the city of Rochester, county of Monroe and State of New York, have invented a new, original, and ornamental Design for a Bridge for an Ophthalmic Mounting, of which the following is a specification, reference being had to the accompanying drawing forming part thereof.

Figure 1 is a front elevation of a bridge for an ophthalmic mounting, showing my new design; and

Figure 2 is a top plan view thereof.

I claim:

The ornamental design for a bridge for an ophthalmic mounting, substantially as shown.

HENRY W. GROM.
